Primary Examiner — Barbara Fox*Assistant Examiner* — Aram Kwon(74) *Attorney, Agent, or Firm* — Birch, Stewart, Kolasch & Birch, LLP(57) **CLAIM**

The ornamental design for an audio player, as shown and described.

DESCRIPTION

FIG. 1 is a front, right side, perspective view of an audio player showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the audio player that form no part of the claimed design.
